UNITED STATES PATENT OFFICE.

WARD B. CARPENTER, OF WEST TOPSHAM, VERMONT.

IMPROVEMENT IN CRIBS.

Specification forming part of Letters Patent No. 141,918, dated August 19, 1873; application filed May 31, 1873.

To all whom it may concern:

Be it known that I, WARD B. CARPENTER, of West Topsham, in county of Orange and State of Vermont, have invented a new and Improved Child's Crib Attachment, of which the following is a specification:

In the accompanying drawing, Figure 1 represents a vertical transverse section of a crib with my attachment in position for rocking; Fig. 2, an end view of the crib with parts broken off, showing the attachment in such a position that the crib rests on the casters; and Fig. 3 is a detail longitudinal section through the crib, with a side view of attachment.

Similar letters of reference indicate corresponding parts.

The object of my invention is to provide an attachment to a crib, by means of which the same can be readily changed from the rocking position into a stationary one without being perceptible to the child sleeping therein, and permitting the quick and easy removal of the crib from one place to another. My invention consists of a slide attachment pivoted centrally to the rockers, made of two halves, having casters at their outer ends, by which the rocking crib can be changed directly into a crib moving on casters.

In the drawing, A represents the crib; B, the rockers, pivoted to the legs thereof; and C the vertical slides moving in recesses in the head and foot boards of the crib A. Each rocker B is made of two halves, pivoted centrally between the legs to the lower end of slide C. The outer ends of the rocker posts B are notched or recessed at the lower side, and provided with the common furniture-casters a in such a manner that the same do not interfere with the rocking motion of rockers B. A longitudinal shaft, b, hangs in staples d of head and foot boards, and is provided with a

crank, e, by which it may be turned between buttons e' of the crib. To disks f of rod b, or their equivalent, are pivoted eccentrically the connecting-rod g, which are also pivoted, with their lower ends, to the slide-pieces C.

On turning the crank e from one button, e', to the other, the slide-pieces C are raised by the eccentric rods g, and the pivoted rocker posts B drawn upward with them till they rest on casters a at the recessed ends thereof. The crib may thereby be easily changed from the rocking position into one resting on casters without disturbing the occupant, and may also be readily moved from place to place. On reversing the crank, the rockers assume their former curved position for the usual purpose.

Having thus described my invention, I claim as new and desire to secure by Letters Patent—

1. A cradle or crib, provided with sectional pivoted rockers to adapt the cradle to be converted into a stationary crib, or vice versa, by simply elevating or depressing said rockers, as herein shown and described.

2. The combination, with the cradle A having recessed head and foot boards, of the slides C pivoted to the adjacent ends of the rockers B, as shown and described, whereby said slides are adapted to be adjusted vertically by means of a suitable device attached to the cradle.

3. In combination with the pivoted rockers B and adjustable slides C, the shaft b, eccentric f, connecting-rod g, and handle or crank e, as and for the purpose specified.

WARD B. CARPENTER.
